UNITED STATES PATENT OFFICE.

HENRY C. BLAIR, OF PHILADELPHIA, PENNSYLVANIA.

FOLDING LAP BOOK-REST.

1,200,073.

Specification of Letters Patent.

Patented Oct. 3, 1916.

Application filed September 17, 1913. Serial No. 790,153.

To all whom it may concern:

Be it known that I, HENRY C. BLAIR, a citizen of the United States, residing at Philadelphia, in the county of Philadelphia, State of Pennsylvania, have invented a new and useful Folding Lap Book-Rest, of which the following is a specification.

My invention relates to improvements in book rests adapted to be held in the lap, 10 and to hold the book at a proper elevation therefrom, and at a proper distance from the reader's eyes.

The object is to provide simple and efficient means for so supporting a book, especially a heavy book. Said device is adapted to be folded in a small compass when not in use.

Referring to the drawings which illustrate merely by way of example, a preferred embodiment of my invention; Figure 1 is a view in perspective of my improved book rack in operative position. Fig. 2 is a rear elevation of same. Fig. 3 is a side elevation with part of the book board broken 25 away. Fig. 4 is a detail of wire loop engaging means, in plan view.

Similar numerals refer to similar parts throughout the several views.

The book rest consists of the book supporting board or body 5, having the usual resilient clamping fingers 6 for engaging the pages of the book. This board is provided with the ledge 7 for supporting the lower edges of the book. The structure supporting the book board 5, consists of a substantially rectangular frame normally adapted to lie in a horizontal plane when in use, and upwardly projecting extensions therefrom disengageably connected with the book board. The rectangular frame is made of two wires or extensions hinged together. Extension 8 is preferably of spring metal and has the two parallel extensions 9 substantially at right angles with the intermediate portion or extension 8. These extensions 9 have portions 10 of their free ends bent slightly out of line with the main extensions 9, as shown in Fig. 3, and are provided with the hooks or lugs 11 at their 50 extremities. The portions 10 are adapted

to engage in the recesses 12 of a strip 13 secured on the back of the board or body 5 at the lower edge thereof. They are held in such position by the resilience of the wire. The wire extension 14 is rectangular in formation and has a hinged engagement as at 15, with extension 8. Extension or wire 14 is provided with the loop 16 with which the brace wire 17 has a hinged engagement. Wire 17 is provided at its free end with a loop 18 which is adapted to be disengageably connected to the under side of the hook board 5 at about the center thereof, by a screw eye 19, turn button or similar device.

As thus assembled the rack is in condition for use. The wire extensions 14 and 8 form a rectangular frame which is adapted to rest upon the reader's knees or lap and the extensions 9 and brace 17 support the book 70 board 5 at a sufficient elevation above the lap to hold the book in most convenient position and at the proper distance from the reader's eyes.

By slightly pressing the extensions 9 toward each other the extensions 10 may be withdrawn from apertures 12, and by turning the screw eye 19, the loop 18 may be withdrawn therefrom, and thus the parts may be readily folded together when not in use.

The device is light, substantial and extremely simple in construction.

What I claim is:—

1. The combination of a book supporting board, a folding supporting structure therefor, comprising a base frame having an intermediate extension and end extension substantially at right angles with the intermediate extension and a second frame pivotally connected with the base frame having resilient terminals, the board provided with recesses for disengageable connection with said terminals and a brace hinged to the base frame and disengageably connected 95 with the board.

2. The combination of a book supporting board, a folding supporting structure therefor, comprising a base frame having an intermediate extension and end extension 100

substantially at right angles with the intermediate extension and a second frame pivotally connected with the base frame having resilient terminals, the board provided with recesses for disengageable connection with said terminals and a brace hinged to the

base frame and adjustably and disengageably connected with the board.

HENRY C. BLAIR.
